RADIATION SHADOW SHIELD

Felix R. Grat and Eugene L. Savettire, Lake Hiawatha,
and George E. Griffin, Cedar Grove, N.J., assignors
to Radiation Machinery Corporation

Filed July 1, 1969, Ser. No. 18,009

Term of patent 14 years

Int. Cl. D24—02

U.S. Cl. D16—2

FIG. 1

FIG. 2

FIG. 4

FIG. 3

FIG. 5

FIG. 6

FIG. 1 is a top plan view of a radiation shadow shield showing our new design;

FIG. 2 is a side view thereof;

FIG. 3 is a front view thereof;

FIG. 4 is a rear view thereof;

FIG. 5 is an enlarged rear perspective view thereof; and

FIG. 6 is a front perspective view thereof.

We claim:

The ornamental design for a radiation shadow shield, as shown and described.
